CHAIN AND BOLT OPERATED BURGLAR ALARM
Yetta B. Spiegel, 310 Riverside Drive, New York, N.Y.
Filed Oct. 14, 1965, Ser. No. 496,098
6 Claims. (Cl. 116—14)

This invention relates to a chain and bolt operated burglar alarm of the audible type.

A principal object of the present invention is the provision of a more efficient, more reliable, more easily installed device of the kind described, which is adapted for use in domestic and commercial establishments, with little or no alteration of its components, to produce warnings of unauthorized opening of doors and the like, as they occur.

Another object of the invention is to provide a chain and bolt locking device adapted to be associated with a conventional chain and bolt locking device for operating a siren to produce a warning sound.

Still another object of the invention is to provide a burglar alarm that is simple and inexpensive, characterized by fewness of parts and economical to manufacture and assemble.

For further comprehension of the invention, and of the objects and advantages thereof, reference will be had to the following description and accompanying drawings and to the appended claims in which the various novel features of the invention are more particularly set forth.

In the accompanying drawings forming a material part of this disclosure:

FIGURE 1 is an elevational view of a door and door jamb equipped with burglar alarm embodying the present invention shown in operative position.

FIG. 2 is a perspective view of the supporting plate on the door jamb.

FIG. 3 is a perspective view of the cooperating blocks and bolts for locking the door and actuating the alarm.

FIG. 4 is a horizontal sectional view taken on the line 4—4 of FIG. 1.

FIG. 5 is an enlarged vertical sectional view taken on the line 5—5 of FIG. 1.

FIG. 6 is a top perspective view of the audible alarm, parts being shown broken away.

Referring now in detail to the various views of the drawings, in FIG. 1 the improved burglar alarm system is shown associated with a door 10 and a door jamb 12. The burglar alarm system includes a rectangular shaped supporting metal plate 14 on the door jamb 12 and a rectangular metal keeper device 16 on the door 10.

The supporting plate 14 is vertically disposed and secured to the door jamb by means of screws 18 passing through holes 20 in the plate. An eye 22 is formed integrally with the body of the plate and is disposed horizontally thereof. An angular hook 24 is formed integrally with the plate 14 above the eye 22 with its free leg 26 extending upwardly.

The keeper device 16 comprises a rectangular shaped base plate 28 and is horizontally disposed and has another plate 30 superimposed thereon and fastened thereto by rivets 32. The plates 28 and 30 are fastened to the door by means of screws 34 passing through aligned holes in the plates 28 and 30. Plate 30 is formed with a hood cover portion 36 integral therewith and extending above the base plate 28 and extending along and over the base plate 28 for the greater portion of its area. The hood portion 36 and the base plate 28 define a compartment 38. The hood cover portion is open at one end as indicated at 40 and is formed with a central guide slot 42 intersecting the open end 40. The outer or intersection end of the slot is formed with curved corner edges 44 to facilitate entrance thereinto. The closed end of the hood cover portion 36 is formed with an opening 46.

2

Conventional door locking mechanism is associated with the plate 14 and keeper device 16 and this mechanism includes a heavy metal chain 48, the oval link 50 at one end extending through the hole in the eye 22 and fastened thereto. The other end of the chain carries a rectangular metal block 52 having a round bolt 54 radiating from one side thereof and extending through a double-loop link 56 at the other end of the chain. A head 58 is formed on the free end of the bolt to prevent removal of the double-loop link 56 from the bolt. The diameter of the bolt 54 is slightly less than the width of the slot 42 to permit the bolt to slide along the slot, and the dimensions of the block 52 are such as to permit the block to slide in the compartment 38. In use, the block 52 is inserted through the open end 40 of the hood cover portion 36 into the compartment 38 where its body spans the slot 42 and engages the edges of the slot to prevent the door 10 from being completely opened as is usual.

In accordance with the present invention however, auxiliary locking mechanism is provided. This mechanism includes another strong chain 60 shorter than the chain 48, the oval link 62 at one end thereof being slipped over the free leg 26 of the hook 24 on plate 14. The other end of the chain has a double-loop link 64 similar to link 56 of chain 48, which double-loop link is looped around a round bolt 66 similar to bolt 54 and is prevented from slipping off bolt 66 by a head 68 on the bolt similar to head 58 of bolt 54. Bolt 66 extends radially from a block 70 similar to block 52. Block 70 slides in the compartment 38 similar to block 52 when pulled by chain 60.

The present invention contemplates housing a wind instrument 74 in the compartment 38 in the path of movement of one or both of the slidable blocks 52 and 70. The instrument 70 is conventional and comprises a bellows structure having a rectangular casing 76 having rigid end walls 78, 80 and a flexible accordion-pleated wall 82 constituting the four sides of the casing. A hole 83 is formed in the center of the end wall 80. A coil spring 84 is interposed between the end walls urging the end walls apart. A siren device 86 is mounted on the inner surface of the end wall 80. The siren device 86 includes a disc-shaped body 88 having spaced holes 90 in annular formation around the periphery thereof communicating with the opening 83 in end wall 80. A reed 92 is mounted on the body 88 and is adapted to cover opposed holes 90 to provide a sound when the end walls are compressed together by the sliding movement of the blocks 52 and 70 upon opening of the door 10.

In operation, a slight opening of the door 10 will cause pulling movement on the chain 60 whereupon block 70 will be moved against block 52 which in turn will compress the casing thereby forcing air past the reed 92 through the holes 90 in the siren and out through the aligned holes 83 and 46 in the end wall 80 and hood 46, respectively, causing a prolonged sound thereby alerting an inmate or inmates to the fact that someone is tampering with the door.

While I have illustrated and described the preferred embodiment of my invention, it is to be understood that I do not limit myself to the precise construction herein disclosed and that various changes and modifications may be made within the scope of the invention as defined in the appended claims.

What is claimed is:

1. In a warning system for premises having an openable door and a door jamb, said system including a plate on the door jamb, a plate on the door in opposed relation to the plate on the door jamb, a hood cover portion over the plate on the door, said hood cover portion being integral with the plate on the door and extending substantially the length of the plate, said hood cover portion and door plate defining a compartment, a bellows

device in said compartment, a siren device mounted in said bellows device at one end thereof, said siren device including a disc shaped body with spaced holes in an annular formation therein, and a rotatable reed adapted to cover opposed holes, and chain and bolt means coacting with the plate on the door jamb and with the hood cover portion on the plate on the door, for locking the door and for compressing the bellows device for forcing air through the siren device to produce a sound.

2. The combination according to claim 1 wherein the bellows device includes a casing rectangular in configuration, said casing having a pair of rigid end walls, one of the end walls having a central opening, an accordion-pleated flexible wall constituting the four sides of the casing, a coil spring interposed between the end walls inside the casing, to urge the end walls apart, the siren device mounted on the inner surface of the perforated wall.

3. The combination according to claim 1 wherein the hood cover portion has an open end and a slot extending centrally thereof intersecting the opening at the end, and wherein said chain and bolt means includes a pair of chains having one end attached to the plate on the door jamb and a bolt and block assembly carried on the other end of each chain, and movable along the slot and compartment, said blocks engaging a fixed portion of the hood cover portion for locking the door, one of the blocks adapted to contact the bellows device for actuating the siren device to produce a sound.

4. The combination according to claim 1 wherein the hood cover portion has an open end and a slot extending centrally thereof and intersecting the open end, and wherein the chain and bolt means includes a first chain having one end fixed to the plate on the door jamb, a bolt carried on the other end of the chain and extending through the slot in the hood cover portion, a block fixed on the inner end of the bolt and slidably in the compartment into contact with said bellows device, a second chain having one end removably attached to the plate on the door jamb, a bolt carried on the other end of the second chain end extending through the slot in the hood cover portion outwardly of the bolt on the first chain, and a block fixed on the inner end of the bolt on the second chain slidably against the first-named block, said blocks engaging a fixed portion of the hood cover portion for locking the door, said blocks being slidable upon opening of the door for

comprising the bellow device for actuating the siren device to produce a sound.

5. The combination according to claim 1 wherein the hood cover portion has an open end and a slot extending centrally thereof and intersecting the opening at the end, and wherein the chain and bolt means includes a first chain having one end fixed to the plate on the door jamb, a bolt carried on the other end of the chain and extending through the slot in the hood cover portion, a block fixed on the inner end of the bolt and slidably in the compartment into contact with said bellows device, a second chain having one end removably attached to the plate on the door jamb, a bolt carried on the other end of the second chain and extending through the slot in the hood cover portion outwardly of the bolt on the first chain, and a block fixed on the inner end of the bolt on the second chain slidably against the first-named block, said blocks engaging a fixed portion of the hood cover portion for locking the door, said blocks being slidable upon opening of the door for compressing the bellow device for actuating the siren device to produce a sound, said second chain being shorter than the first chain so that upon opening of the door the second chain is pulled first moving its block against the block of the first chain which in turn compresses the bellows device for actuating the siren device producing a sound therein.

6. The combination according to claim 5 wherein the bellows device includes a casing rectangular in configuration, said casing having a pair of rigid end walls, one of the end walls having a central opening, an accordion-pleated flexible wall constituting the four sides of the casing, a coil spring interposed between the end walls inside the casing, to urge the end walls apart, a siren device mounted on the inner surface of the perforated wall adapted to be actuated by air forced therethrough and through the opening in the end wall upon compressing of the casing by the sliding blocks.
